Fig.4

Fig.5

Fig.3

FIGURE 1 is a front elevational view of my gauge calibrator;

FIGURE 2 is a plan view of my gauge calibrator;

FIGURE 3 is a bottom view of my gauge calibrator;

FIGURE 4 is a right-hand end view of my gauge calibrator; and

FIGURE 5 is a sectional view taken through the line 5-5 of FIGURE 2 but omitting a showing of the internal features of my gauge calibrator.

The dominant features reside in the portion shown in full lines, the clamp element shown in broken lines in

FIGURES 1 and 2 being omitted from FIGURES 4 and 5 for convenience of illustration only.

I claim:

The ornamental design for a gauge calibrator or the like, substantially as shown.
